TOBACCO POUCH AND THE LIKE

Everett G. Clements and Saul E. Spector,
Washington, D. C.

Application April 20, 1931, Serial No. 531,542

3 Claims. (Cl. 206—41)

Our invention relates to improvements in tobacco pouches or other containers, and more particularly to tobacco tamping means forming a substantially rigid extension of an interior wall of such pouches or containers, and has for its object to facilitate the packing of tobacco within the bowl of a pipe inserted into the pouch or container for filling.

A further feature of the invention consists in immovable means shaped to pass within the bowl of a pipe when the pipe is inserted into a pouch or other container and moved through the tobacco therein towards one end thereof.

A still further object consists in the provision of a substantially rigid tamping device for pouches or other containers, the device being provided with means for detachably securing the same within a wall of the pouch or container wherever found desirable.

Another purpose is the provision of such a device having no moving elements and constructed from simple and inexpensive parts.

The above and other objects will be apparent from the detailed description hereinafter set out, and from the drawing appended hereto and made a part hereof, and in which

Fig. 1 is a perspective view showing the invention applied to a tobacco pouch and illustrating the manner of its use as an aid in tamping tobacco within the bowl of a pipe, when filling the same in usual fashion;

Fig. 2 is a view showing one manner of securing our novel attachment to a pouch when made as a separate article of manufacture; the pouch being shown broken away and the attachment shown partly in section;

Fig. 3 is a view partly in section taken on line 3—3 of Fig. 2;

Fig. 4 is a side elevation showing a slightly modified form of securing the tamping device to the pouch;

Fig. 5 is a view taken on line 5—5 of Fig. 4.

Heretofore, it has been customary when filling a pipe to insert the bowl thereof into the mass of tobacco within a pouch and to tamp the tobacco within the bowl by inserting a finger therewithin, either during the filling operation or subsequent thereto. This procedure has been found to be highly unsatisfactory due to the fact that the finger not only becomes stained by the tobacco, but also is made dirty by the black ash which lines the inner surface of the pipe bowl. With the present invention, however, the above objectionable steps are rendered unnecessary in a simple, efficient manner. The device is constructed so as

to extend from a wall within the pouch to cooperate with the bowl of the pipe when filling the same with tobacco in the usual fashion, without requiring withdrawal of the pipe from the pouch and without recourse to the operation of movable parts.

By reference to the drawing and particularly Figs. 1, 2 and 3 thereof, it will be noted that the character C indicates a conventional tobacco pouch which is shown as held in one hand of the smoker, the other hand grasping the stem of the pipe P, forcing the bowl B thereof, after filling the same with the tobacco T, over our novel tamping attachment generally designated as A.

The tamping device A comprises a body member 10, preferably circular in cross-section, having tapered heads 11 and 12, the latter head being extended in the form of a stem 13. To rigidly support the tamping device A, the stem 13 is secured to or made in part with an anchor plate which is preferably shaped to provide opposed surfaces 14 and 15 to engage and embrace the edges 16 and 17 of the seam generally located at one end of the pouch. It will be seen that the anchor plate, formed as described, functions to reinforce the seam at the end of the pouch by compressing the edges of the seam at 18, and by reversely curving the vertical edges of the plate, as indicated at 19 and 20, the device is securely nested within the folds 21 and 21a of the pouch at each side of the seam.

To render the device readily attachable to pouches of standard construction and design, the body member may be internally threaded at 22 to receive a suitable securing means, such as 23. The securing means is illustrated as having an elongated flattened head 24 adapted to be partially concealed within the seam of the pouch when its threaded stud 25 is threaded into the body member 10 to compress the material of the pouch therebetween.

While various means may be provided for permanently or detachably securing the body member in a desired position within a pouch or other tobacco container, we have illustrated but two forms herein. The form shown in Figs. 3 and 4 differs from that already described by the provision of integral prongs 30 and 30a struck from the anchor plate which are adapted to be passed through the material of the container and clinched to securely and rigidly support the device in operative position within the container. When the prongs are thus clinched the pointed ends 32 and 33 are reversely bent as at 34 and

35 and forced into the seam of the pouch, as indicated at 36.

The tamping device may be made in any well-known or approved manner, such as by molding or casting from metal, hard rubber or other plastic compositions, or by stamping from sheet materials, it being only important that the dimensions of the body be of such size as to readily pass within the bowl of the pipe and, when so formed, 10 will not cause any bulging of the pouch.

From the above description it will be apparent that we have constructed a device of few parts which are simple to manufacture and well adapted for the purpose specified. It will be appreciated that the device may be sold independently of the pouch and may be readily attached to pouches or containers now in use.

Various modifications other than those specifically shown and above described will be apparent 20 to persons skilled in the art, and it is our intention to cover all such modifications and to be limited in this respect only as may be necessary by the scope of the claims hereto appended.

We claim:

25 1. In a tobacco receptacle having an elongated filling and outlet opening extending between the end walls thereof, a rigidly braced tobacco tamping element having a head shaped for cooperation with the bowl of a pipe, and means detachably 30 securing the element to one of the end walls to extend into the pouch substantially adjacent and parallel to the plane of the opening, whereby a

pipe can be filled and tamped by scooping the same through the exposed surface of the tobacco.

2. In a flexible tobacco pouch open along one longitudinal side thereof and having inturned seams at its ends, a tobacco tamping element provided with a head shaped for cooperation with the bowl of a pipe, and means associated with the head having portions embracing a seam to rigidly support, brace and secure the element substantially adjacent to and parallel with the open side of the pouch, whereby a pipe can be filled and tamped by scooping the same through the exposed surface of the tobacco. 80 85

3. A tobacco container including a flexible wall portion therefor and having an accessible opening to the tobacco contents, a tamping device within the container and having a point of attachment with the flexible wall portion and extending substantially parallel to the opening, the size, shape and relationship between the opening and tamping device being such as to permit the insertion of a pipe bowl through the opening into the tobacco contents and thereafter permitting a sweep of the bowl through the tobacco toward and over the tamping device, there being a rigid 90 95 bracing means at the aforesaid point of attachment for engaging such portion of said flexible wall as will hold the tamping device in proper tamping position. 100 105
